FOUNTAIN SYRINGE WATER BAG

Filed July 5, 1928

UNITED STATES PATENT OFFICE.

AMANDA R. LOGAN, OF EAST CHELMSFORD, MASSACHUSETTS.

FOUNTAIN SYRINGE WATER BAG.

Application filed July 5, 1928. Serial No. 290,568.

My invention relates to water bags of fountain syringes. These bags are usually made of rubber so molded as to lie collapsed flat when empty, the mouth of the bag usually having a tab with reinforced aperture by which the bag may be hung up. In order to open the mouth of the bag so that the same may be filled the sides of the mouth must be pressed toward one another to cause the front and back walls of the mouth to separate or open up. Difficulty has been experienced in filling such bags since the user must hold the bag open by grasping the neck and squeezing the sides together and thus hold the bag in one hand while filling it with the other. As the bag fills and gets heavier it frequently slips out of the hand, spilling the contents and making a mess generally.

My invention therefore has for its principal object to provide a simple, cheap and effective means, always present, by which the bag's mouth may be held open, thus enabling the user to hold the bag by grasping the tab with one hand while filling the bag with the other. This makes it easier to fill the bag without spilling as well as effecting a saving of time in the filling operation.

Further, it is an object to provide an attachment for syringe water bags which will always be ready for use and which will not mar or injure the bag or add materially to its cost of manufacture.

Other objects will in part be obvious and in part be pointed out hereinafter.

To the attainment of the aforesaid objects and ends, my invention consists in the novel details of construction and in the combination, connection and arrangement of parts, hereinafter more fully described and then pointed out in the claims.

In the drawing:

Figure 1 is a perspective view of a fountain syringe water bag with my invention applied, looking at the front.

Figure 2 is a similar view taken from the back.

Figure 3 is an enlarged perspective view of the upper portion of the mouth of the bag with my invention applied in use.

Figure 4 is a plan view of Figure 3.

Figure 5 is a detail view of the rigid member per se.

Figure 6 is a detail sectional view of the rigid member.

Figure 7 is a detail sectional view of one

of the button members showing details of construction.

In the drawing in which like numerals of reference indicate like parts in all of the figures, 1 represents the water bag whose neck 2 has the usual reinforced bead 5 at the rim of its mouth 4. The neck is also provided with the usual holding tab 3.

When my invention is used the bag will be provided with a button 6 secured to the front portion of the neck, preferably about one-fourth the distance from a side, while a second button 6 is correspondingly located on the back wall of the neck. These buttons may be wholly of rubber, or they may be composed of metal or metal encased in rubber. When the latter type of button is used the button may have a shank 8, a back head 7 and a covering 10. Where the button is secured to the bag it will be suitably reinforced at 9 to prevent breakage or tearing of the bag.

In carrying out my invention there is also provided a rigid member 11, similar to a garter slide, the larger end of which has a hole 14 by means of which it may permanently be swivelled on one of the button shanks. The member 11 has an elongated slot, that end 15 adjacent the hole 14 being of a sufficient diameter to pass the other button's head 85 through the slot. The slot tapers from the larger end 15 toward the other end of the member to a diameter at 16 approximately that of the button's shank. The member 11 may be wholly of metal or metal 12 encased in rubber 13, or other suitable non-corrosive substances.

Normally the member 11 lies flat against the bag but when it is desired to fill the bag the button on the front is passed into the opening 15 and brought to the end 16. This causes the member 11 to press in the adjacent side of the neck and hold the bag's mouth open as shown in Figure 3.

From the foregoing description, taken in connection with the accompanying drawing, it is thought the construction, operation and advantages of my invention will be clear to those skilled in the art, and I desire it understood that slight changes in the details of construction, combination and arrangement of parts may be made without departing from the spirit of the invention or the scope of the appended claims.

What I claim is:

1. In combination with a water bag, releasable means secured to the bag and adapted when in one position to hold the bag's mouth open and when in another position to lie flat against the bag.
2. In combination with a water bag of flexible material having a mouth normally lying closed, of a member swivelly secured to one face of the bag at the neck and adapted to be passed around the side of the neck and means for securing said member to the front wall of the neck, said member being of sufficient rigidity to press in the side of the neck and thereby hold the neck open.
3. In water bags, a neck of rubber having provisions continuously tending to hold the

neck closed, a member secured to one of the flat walls of the neck and adapted to be passed around the side of the neck, and means for securing the free end of said member to the other flat wall of the neck when passed around the side of the neck thereby to hold the mouth of the bag open substantially as specified.

4. In combination with a water bag having a mouth normally collapsed, of a device co-operatively connected with the bag and adapted when in one position to hold the mouth open, and when in another position to release the mouth and permit it to close, substantially as shown and described.

AMANDA R. LOGAN.
